IMMERSION HEATER FOR BITUMINOUS MATERIALS AND THE LIKE

George P. Kittel, Englewood, N. J.

Application November 17, 1937, Serial No. 175,045

2 Claims. (Cl. 126—360)

This invention relates generally to means for heating and melting a variety of materials, the same being more particularly directed to an improved apparatus for melting bituminous materials, such as asphalt, pitch, tar, wax, road oils and the like.

Heretofore, such materials have been heated or melted either by applying heat to the outside of a receptacle containing the materials or by introducing heat through a flue extending through the container which is removably bolted in place.

While greater efficiency is obtained from the flue type heating means, due to the more rapid heating and melting of the materials in proportion to the amount of heat expended, it has been open mainly to the objection that considerable difficulty is experienced in cleaning the flue and receptacle, due to the fact that materials of the character enumerated tend to rapidly foul or coke the heating surfaces, and the labor involved in the frequent removal of the flue for cleaning has proven such a disadvantage that its use has been materially limited and many have returned to the old practice of applying heat to the outside of ordinary containers.

The present invention comprehends an improved heating apparatus of the indicated character, either as a unit applicable to any type of receptacle for melting materials or in combination with a particular type of receptacle with means for detachably connecting the same thereto.

More particularly the invention is concerned with an immersion heater for melting bituminous materials or the like in an open top receptacle which is so constructed and arranged so as to facilitate and expedite the emplacement of the immersion heater within the receptacle and its removal from the receptacle whereby when separated the surfaces of the heater and receptacle may be readily cleaned and freed from the materials which adhere thereto.

The invention further resides in an improved heating unit for melting bituminous materials or the like which is so constructed and arranged as to obtain a maximum efficiency from the heat developed by the burner element associated therewith.

As a further feature the invention embodies an immersion heater for the purpose set forth in which the burner is constructed as an independent unit, removably associated therewith and separable therefrom, so as to facilitate the handling and cleaning of the heater when sepa-

rated from the burner element and when removed from the receptacle.

With the above enumerated and other objects in view, the invention is set forth in greater detail in the following specification, illustrated in the accompanying drawings, disclosing one way in which the invention may be carried into practice, while the appended claims cover variations or modifications falling within the scope of the invention.

In the drawings:

Fig. 1 is a perspective view of a heating apparatus constructed in accordance with the invention.

Fig. 2 is a longitudinal sectional view through the heating apparatus illustrating the same positioned within a receptacle.

Fig. 3 is a sectional plan view thereof taken approximately on the line 3—3 of Fig. 2.

Fig. 4 is a transverse sectional view taken approximately on the line 4—4 of Fig. 2.

Fig. 5 is a perspective view of the burner element used in conjunction with the heater.

Referring to the drawings by characters of reference, 10 designates a receptacle of the open top type adapted to receive the materials to be heated and melted and which may be provided with an outlet cock 11 for drawing off the melted material.

The apparatus for heating and melting the materials comprises a cover panel 12 of sheet metal which is adapted to be supported upon the upper edge of the receptacle adjacent to one end thereof. The cover panel is formed with a substantially central opening 13 from which a well 14 depends, the said well being open at the top and provided with continuous side walls 15 and a bottom 16. The side wall facing the remote end of the receptacle 10 is formed with an opening 17 to which is attached one end of the tubular lead 18 of a flue unit which extends horizontally therefrom towards the remote end of the receptacle, said lead having communication with the interior of the well at its juncture therewith.

One or more reversely directed tubular flue leads 19, in the present instance two being shown, are connected to and communicate at one end with the remaining end of the flue lead 18 by branch conduits 20. The leads 19 extend towards the well 14 and are provided with upwardly directed outlet terminals 21 which extend through openings in the cover panel 12. In order to space the flue leads and the bottom 16 from the walls of the receptacle so that the ma-

terial being heated and melted will completely surround the heating apparatus in which it is immersed, feet 22 are formed on and depend from the flue leads 19.

5 The heating apparatus further includes a burner 23 of a type which projects a directed flame such as the vaporizing torch type, and which receives its fuel supply through a tubular conduit 24 extending upwardly therefrom, through the 10 open top of the well 14, the burner being provided with a supporting base 25 which is adapted to rest upon the bottom wall 16 of the well 14 so as to project the flame through the opening 17 and longitudinally of the flue lead 18. The 15 burner is, therefore, removably located within the well 14, which serves as a housing therefor, and may be separated from the remainder of the heating apparatus to facilitate handling of the device and cleaning of the same to free the 20 surfaces of the material which adhere thereto.

In the present instance, the receptacle 10 is provided with inwardly projecting lugs 26 having threaded apertures for receiving the set screws 27 which are rotatably carried by the cover panel 25 12 thereby affording means for removably securing the heating apparatus in place within the receptacle. The set screws also serve as a means to rigidly impinge the feet 22 against the inner 30 surface of the wall of the receptacle. If desired, the uncovered open top of the receptacle 10 may be closed by means of a cover member 30 having a flanged margin 31 fitting upon the upper edge of the receptacle 10, while one of the flanged margins 31 rests upon the cover panel 12 and is 35 slotted to receive the apertured lug 32 provided on the cover panel 12. In order to brace the cover panel, angle braces 33 may be provided which extend laterally and upwardly from opposite side walls 15 of the well 14. To facilitate lifting and 40 handling of the heating unit, a handle 34 is preferably provided on the branch conduits 20 which join and establish communication between the flue leads 18 and 19.

What is claimed is:

45 1. Apparatus for heating and melting bituminous materials including in combination an open top receptacle for said materials, and a removable immersion heating unit comprising a cover panel provided with an opening and adapted to

be supported on the top of the receptacle adjacent one end thereof, an open top housing secured at its upper end to the cover at the opening and depending therefrom, a flue having a lead secured to and communicating at one end with the lower 5 portion of said housing and extending substantially horizontally towards the remote end of the receptacle, a pair of horizontally disposed reversely directed side leads communicating at one end with the remaining end of the first lead and 10 extending substantially horizontally therefrom towards the housing, an upwardly directed exhaust terminal at the remaining end of each side lead extending upwardly through and secured to said cover panel, and a jet-type burner having a 15 directed flame adapted to be positioned in said housing so that the flame is directed into and longitudinally of said first-mentioned flue lead.

2. Apparatus for heating and melting bituminous materials including in combination an open 20 top receptacle for said materials having a removable cover extending from one end towards and spaced from the other end of said receptacle, and a removable immersion heating unit comprising a cover panel provided with an opening and 25 adapted to be supported on the top of the receptacle at and covering the uncovered end thereof, an open top housing secured at its upper end to the cover at the opening and depending therefrom, a flue having a lead secured to and communicating at one end with the lower portion 30 of said housing and extending substantially horizontally towards the remote end of the receptacle, a reversely directed lead communicating at one end with the remaining end of the first lead and 35 extending substantially horizontally towards the housing, an upwardly directed exhaust terminal at the remaining end of said reversely directed lead extending upwardly through said cover panel, a jet-type burner having a directed flame 40 adapted to be positioned in said housing so that the flame is directed into and longitudinally of said first-mentioned flue lead, and cooperating means provided respectively on said receptacle, the cover therefor and on the cover panel for 45 detachably connecting the same in assembled relation.

GEORGE P. KITTEL.
